PROPELLING MECHANISM

Application filed April 2, 1930. Serial No. 441,006.

The invention relates to propelling mechanism for water craft.

The object of the invention is to provide a novel propeller arrangement and drive whereby the efficiency of the propelling unit may be greatly increased with only a small expenditure of additional energy. More particularly, the invention consists in the association of two propellers of substantially the same size and of opposite pitch mounted adjacent each other, each on a drive shaft arranged concentric to and driven in the opposite direction to the other shaft.

15 The invention further consists in the several features hereinafter set forth and more particularly defined by claims at the conclusion hereof.

In the drawings Fig. 1 is an elevation 20 view of an outboard motor equipped with propelling mechanism embodying the invention;

Fig. 2 is a detail vertical, sectional view through the propelling mechanism;

25 Fig. 3 is a detail sectional view taken on the line 3—3 of Fig. 2;

Referring to Figs. 1 to 3, inclusive, the numeral 6 designates a rowboat, 7 an outboard motor secured thereto in known manner, embodying the usual engine suitably connected to drive the vertically disposed transmission shaft 8 suitably journaled in the casing 9.

The shaft 8 carries a bevel gear 10 meshing with oppositely disposed bevel gears 11 and 12, respectively fixed to propeller shafts 13 and 14, the shaft 14 being hollow and journaled in a bearing portion 15 of the casing, while the shaft 13 is journaled at 30 one end 16 in the casing and extends through and is rotatably mounted within the hollow shaft 14. Thus the shafts 13 and 14 are concentrically mounted and because of the gearing above described are driven in opposite directions and at the same speed.

The shaft 14 has a propeller 17 mounted thereon against a shoulder 18 and securely clamped thereto by a nut 19 on the threaded end of said shaft.

45 The shaft 13 has a propeller 20 mounted

thereon to rotate therewith in any suitable manner, as by means of clamping nuts 21 and 22.

The propellers 17 and 20 are of substantially the same pitch ratio, but of opposite 55 pitch and of substantially the same size.

The gear ratio of the drive mechanism above described is unity, so that the propellers 17 and 20 are driven at substantially the same speed.

60 It will be observed that the two oppositely revolving propellers are mounted adjacent each other so that the first propeller forces the water or air against the other so that the second propeller can act with more force 65

thereon. That this action does occur has been demonstrated by trials of a device embodying the invention, wherein it has been found that for an additional expenditure 70 of energy of only one and four-tenths per cent over that required to drive one propeller, I obtain almost one-third more tractive effort by the use of the two over a single propeller. Thus, it will be under-

75 stood that the propellers are arranged close enough together that the reactive components of one are within the range of action 75

of the other and where the pitch of the propellers is great, the propellers should be arranged more closely together than where the 80

pitch is smaller, since with the greater pitch the water or air streams against which the 85

the second propeller works are shorter than those where the pitch is less. In the use 90

of these two propellers it will be observed 95 that the first propeller overcomes the inertia or the resistance of the mass in which the propeller is working and that the second propeller is, therefore, substantially relieved of this duty and bores its way through the stream or immediate wake of the first propeller.

While the two-blade propellers have been shown, it is obvious that three or more blades may be used on the propellers for larger craft and while an outboard motor is shown, it is obvious that the invention may be applied to other forms of marine propulsion apparatus without departing from the spirit of this invention.

I, therefore, desire it to be understood that this invention is not to be limited to any particular form or arrangement of parts except insofar as such limitations are included in the claim.

What I claim as my invention is:

In a propelling mechanism, the combination with an underwater housing, of a power transmission shaft journalled in said housing and extending lengthwise thereof and provided with a bevel gear, a sleeve shaft extending at right angles to said first named shaft and journalled in one end of said housing and provided with a bevel gear meshing with said first named gear and having a shoulder exterior of said housing, a propeller mounted on said second sleeve shaft and abutting said shoulder, a third shaft extending at right angles to said first shaft and journalled in said housing and extending through said sleeve shaft and provided with a bevel gear meshing with said first named bevel gear, and a propeller mounted on the outer end of said third shaft, said propellers being of substantially similar pitch ratio and size but of opposite pitch and mounted adjacent each other, said second and third named bevel gears being disposed on opposite sides of said first named bevel gear and being of the same pitch diameter.

In testimony whereof, I affix my signature:

JOHN STECHAUNER.
